UNITED STATES PATENT OFFICE.

CHARLES R. FARGO, OF CHICAGO, ILLINOIS, ASSIGNOR TO WILSON-JONES LOOSE LEAF CO., OF CHICAGO, ILLINOIS, A CORPORATION OF ILLINOIS.

LOOSE-LEAF-BINDER SUPPORT.

Application filed July 12, 1918. Serial No. 244,531.

To all whom it may concern:

Be it known that I, CHARLES R. FARGO, a citizen of the United States, and a resident of the city of Chicago, in the county 5 of Cook and State of Illinois, have invented certain new and useful Improvements in a Loose-Leaf-Binder Support; and I do hereby declare that the following is a full, clear, and exact description of the same, reference 10 being had to the accompanying drawings, and to the numerals of reference marked thereon, which form a part of this specification.

My invention has reference more particularly to a device for adjustably supporting loose leaf binders so as to facilitate manipulation and use of the binder and leaves, and also has reference to a loose leaf binder which is particularly adapted for use with 20 a support of this character.

In using loose leaf books, and particularly in what is known as machine book-keeping, wherein the leaves are assembled and contained in a loose leaf binder which is adapted so that the various leaves thereof may be selected and removed to have entries made thereon and then replaced in proper relation with the other leaves of the binder, it is desirable that the covers of the binder 30 may be separated and held in proper position so that the leaves lean against one of the covers in convenient view and so that selection and removal of the leaves can be easily effected, and also so that the other 35 cover of the binder is held in position to have the leaves which are taken from the position against the other cover laid thereon in position so that the binder may be readily reassembled with the leaves in their proper 40 sequence when the work is completed. To this end, it is not only necessary that a suitable binder be employed for the leaves which permits the necessary separation and arrangement of the covers thereof, together 45 with means which will hold the leaves in the proper alignment when the covers are separated and also permit ready removal and insure replacement of the leaves in proper relation, but it is also desirable to 50 provide means for supporting the binder and the leaves which will enable the covers to be readily separated and replaced and will hold the parts of the binder and the leaves in proper position to facilitate selection, removal and transfer of the leaves

from one position to the other and which will enable the operator to secure perfect adjustment or positioning of the parts and enable him to manipulate the binder and perform the work conveniently and without 60 loss of time.

It is an object therefore of my invention to provide an adjustable support for loose leaf binders and leaves which enables the binder to be readily assembled and dis-assembled thereon and facilitates manipulation and replacement of the leaves in the 65 binder.

It is a further object of my invention to provide a support which may be adjusted to enable the covers of the binder to be easily detached and separated and which may also be adjusted to facilitate reassembling the binder covers and leaves after the work 70 thereon is completed.

Another object of my invention is to provide a loose leaf binder tray or support having a base for engaging the lower edges of the leaves, and a support for the cover pivotally related thereto which may be adjusted to secure the desired upsetting of the leaves to facilitate selection thereof.

Another object of my invention is to provide a support for a loose leaf binder having an adjustable support for each cover of 85 the binder whereby the angular relation of the cover support may be adjusted to facilitate use of the binder on the support.

Another object of my invention is to provide a support for a loose leaf binder adapted for interengagement with parts on the binder to locate and hold the parts of the binder in a predetermined position thereon.

Another object of my invention is to provide a binder with separable covers which is adapted to co-operate with a binder support, and which is adjustable in width to accommodate a varying number of leaves.

Another object of my invention is to provide a binder which is adjustable to accommodate a varying number of leaves between the covers thereof, and which is adapted to have the covers separated and placed on a binder support to permit selection and removal of the leaves, and wherein an extensible, resilient locking member is employed which is adapted to be removed and replaced without removing the binder from the support and which is adapted to be compressed between the covers of the 100 105 110

binder so that separation of the binder covers is required to enable the leaves to be removed from the binder.

My invention also has other important 5 objects which will appear from the following specification and the accompanying drawings, which illustrate and describe a preferred form of my invention.

On the drawings:

- 10 Figure 1 is a front perspective view of the support and open binder thereon showing the leaves of the binder set up ready for selection and transfer to the disposed-of side of the binder.
- 15 Figure 2 shows a similar view with all the leaves transferred to the disposed-of side of the binder and the locking pin in place, the support for said disposed-of side of the binder being dropped down from the position shown in Figure 1, to the position for re-assembling the other cover of the binder thereon.

Figure 3 is an end view of the parts shown in Figure 1, illustrating adjustments thereof.

- 25 Figure 4 is a top or plan view of the support with the binder removed.

Figure 5 is a view looking at the right hand end of Figure 4.

- 30 Figure 6 is a view looking at the left hand end of Figure 4.

Figure 7 is an enlarged sectional view on the line 7—7 of Figure 4.

- 35 Figure 8 is an enlarged fragmentary sectional view on the line 8—8 of Figure 5, showing the supporting brace connection.

Figure 9 is a similar view on the line 9—9 of Figure 5, showing the manner of detaching the supporting brace.

- 40 Figure 10 is a fragmentary view showing the detachable hinge connection of the side member of the support.

Figure 11 is an enlarged fragmentary sectional view of the hinge connection on the line 11—11 of Figure 5.

- 45 Figure 12 is a similar view on the line 12—12 of Figure 6.

Figure 13 is a view similar to Figure 12 showing the position which the binder clamp plate occupies therein.

- 50 Figure 14 is a fragmentary view of the adjustable supporting brace.

Figure 15 is an enlarged sectional view on the line 15—15 of Figure 14.

- 55 Figure 16 is a view looking at the rear end of the binder showing the clamp plates thereof in section.

Figure 17 is an enlarged sectional view of the post lock on the line 17—17 of Figure 16.

- 60 Figure 18 is a sectional view on the line 18—18 of Figure 17.

Figure 19 is an enlarged longitudinal view of the extensible locking pin for locking the leaves in the binder.

- 65 As shown on the drawings:

The binder support is constructed with a

pair of parallel supporting rails or strips 1, which are suitably spaced and have a foot or bearing 2, at each end which may be of rubber so as not to mar the surface upon which support is placed. An angular division plate 3, which has a supporting and stiffening flange 4, at each side thereof has the ends of the flanges connected with the strips 1, by means of the screws as shown in Figure 2, or otherwise so as to be secured transversely thereto, intermediate of the ends of the strips 1, and hold the strips in the desired separated relation and be supported thereby.

The sides 5 and 6, of this division plate are inclined downwardly from the elevated center thereof and serve to support, or co-operate with posts of the binder placed thereon, to support the butt or binding edges of the leaves of the binder when mounted thereon and may be termed end members.

The inclined side 5 is designed to support the leaves of the binder in the initial position ready for selection and manipulation by the operator and has a number of rows of slots or elongated perforations 7, said rows being parallel with the upper edge of the plate 5 and extending from end to end thereof to provide a detachable hinge connection for the plate or side member 8, against which the cover 9 of the binder leans, the said plate 8 having hooks or lugs 10, at its lower edge which are adapted to be inserted in a row of the slots to support the lower edge of the plate 8, at a distance from the upper edge of the angular plate 3, suitable to the thickness of the binder or quantity of leaves.

For adjustably supporting the plate 8, at various degrees of inclination there is a bracket thereunder comprising a U-shaped brace 11, the intermediate portion of which engages the outer face of the plate 8, and the arms of which are telescoped in the tubes or sleeves 12, which latter are pivoted at their lower ends to the outer ends of the strips 1, as at 13, so that the bracket may be swung to engage at different places against the plate 8. These tubes 12 are slotted longitudinally as at 14, and the edges of the slots are oppositely notched at intervals, as at 15, and there is a thumb screw 16 inserted through the slot and threaded into the lower end of each arm of the U-shaped brace 11. This screw has a concave washer 17 thereon, with a transverse rib 18 or other formation on the inner face, at each side of the screw adapted to be seated and held in the notches 15 by means of the screw 16 for providing an adjustment for securely holding the U brace in different positions of elevation.

The plate 8 is shown herein as constructed of sheet metal, although it may be otherwise made if desired, and has a pair of suitably

- spaced lugs or hooks 19 adjacent the upper edge thereof and a similar pair of lugs or hooks 20 spaced a distance from said upper edge, which said lugs or hooks are stamped 5 outwardly from the sheet metal plate 8 or otherwise provided on the outer face thereof so as to engage the intermediate portion of the U-shaped brace 11 at several places and permit quick adjustment of the plate 10. 8, and as is apparent the plate 8 may be lifted and the brace 11 swung to be engaged by either the lugs 19 or 20 to change the inclination of the plate 8, or the U-shape brace 11 may be adjusted in the sleeves 12, 15 by loosening the thumb screws 16, so as to raise or lower the brace 11, and thereby afford an extensive range of adjustment for the plate 8. A strap 21 is attached to the outer face of the plate 8 intermediate of 20 the ends thereof and extends from a point below the lugs 20 upwardly and serves as a retaining means to prevent such separation of the brace 11 from the plate 8 as would allow the plate to drop down to an 25 excessive extent, and at the same time permits adjustment of this brace to engage either set of lugs 19 or 20. The upper end of this strap engages under a clip 22, and forms a snap fastening to permit assembling 30 and removing the brace 11 from confinement by the strap 21, as shown in Figure 9.
- The other face 6, of the angle plate 3, is adapted to engage the butt or binding edges of the leaves of the binder as they 35 are transferred from the other side of the support and has a row of slots 23, along the lower edge thereof through which the lugs 24, at the lower edge of the plate or side member 25, are inserted to permit piv- 40 otal movement of said plate, this plate, together with the face 6, of the division plate 3, forming a tray to receive the detached cover 26 of the binder and the disposed-of leaves. This plate 25, similarly to the plate 45 8, is provided with a pair of spaced outwardly stamped hooks or lugs 27, adjacent the upper edge and a similar pair 28, at a distance from the upper edge, each pair being adapted to engage the intermediate 50 portion of the U-shaped brace 29, the arms of which are pivoted at 30 to the outer ends of the strips 1, so that it may be swung to engage either set of lugs 27 or 28, to hold the plate 25 in two positions of adjustment. 55 Notches 31 are provided on the inner face of each strip 1 adjacent the slots 7 and 23 at the base of the plates 5 and 6, respectively, to admit the attaching lugs 10 and 24 respectively.
- 60 The binder support may be used or may be adapted to be used with any desired type of binder, but I have shown herein a type of binder which I prefer to use therewith, comprising the covers 9 and 26, each 65 of which has a clamp plate or shell 32 and 33, respectively, hinged to the inner edge thereof. These clamp plates are adapted to be connected together to hold the leaves of the binder therebetween and may be disconnected not only to permit removal of 70 the leaves but also to be placed in separated position on the tray or support to enable section and removal and replacement of the leaves by the operator to be easily effected.
- In the method employed quite extensively 75 at the present time for keeping records, it is customary to remove the leaf entirely from the binder and make the entry thereon whereupon it is returned to its proper position in the binder, and it is necessary, in 80 order that this may be conveniently done, that the leaves may be readily removed or lifted directly off without hindrance by or the need of disengagement from any locking contrivances that may be employed for 85 holding the leaves in place in the binder, and it is also necessary that such locking contrivances be employed to hold the leaves securely in the binder when it is assembled or closed. It is also desirable that the leaves 90 may be held in proper alignment when placed on the plate 5 against the support 8, and that they may also be easily and quickly replaced in proper alignment at the other side of the tray on the support 25, 95 or that certain leaves indicated at 40 may be set at one side of or out of alignment with the other leaves and the binder assembled with the leaves bound in this position as shown in Figure 16 so that such 100 leaves may be readily distinguished from the others owing to the fact that they are placed in the binder so that they project beyond the side of the other leaves.
- In order that the foregoing may be accomplished, the leaves 34, of the binder are provided at their inner edges with notches 35, which are equally spaced from each other and entirely open at the butt edge of the leaf and serve as guides to engage posts of 105 the binder and insure the desired alignment or offsetting of the leaves, and intermediate of the notches 35, the leaves 34 have perforations 36, which are equally spaced from each other and from the notches 35, 110 and are entirely closed so as to be engaged by a locking pin of the binder to hold the leaves from removal therefrom.
- The covers of the binder are made extra 115 long so as to cover the offset leaves 40, as shown in Figure 16, and are adjustably connected together so as to make a binder of variable width to accommodate a greater or less number of leaves, and for this purpose the clamp plate 32 of the back cover 9 has a pair of sectional posts 37, permanently attached thereto and spaced so as to be engaged by the outer notches 35, of the leaves 34, when placed in the normal position, 120 and there are corresponding openings 38, in 125
- 130

the opposite clamp plate 33, through which the posts 37 may be inserted and locked in any position of adjustment by means of locking mechanism, which clamps against 5 the posts 37.

The clamp plates 32 and 33 may be of any suitable construction which will effect the purpose of binding and holding the covers and leaves together, but for the purpose 10 of illustration I have shown a structure similar to that forming a part of my application, Serial No. 234,611, filed May 15, 1918, having the clamp plates constructed of sheet metal in the form of a tubular shell, 15 within which the base blocks 39 of the stationary posts and the blocks 41 of the locking mechanism and also socket blocks 42, 43 and 44 are secured for holding and locking the various posts in place therebetween. 20 The block 41 has a perforation therethrough in line with perforations in the inner and outer walls of the shell 33, through which the ends of the posts 37 are adapted to be inserted, and there is a groove 45 in a plane 25 parallel with the post opening in the block 41 and leading thereinto at an acute angle, in which is mounted a ball 46, which, by reason of its movement in the groove 45, is adapted to wedge against the post in the opening in the block and lock same from withdrawal. 30 The ball moves outwardly from the post perforation when moved in the direction in which the post is inserted, thus enabling the post to be inserted without interference, and there is a lever 47 pivoted on an extension of the block 41 and forked at one end to straddle the ball 46 for controlling the operation of the ball. This 35 lever is engaged by a spring 48 to normally impel the ball to the locking position and has a button 49 at the outer end which projects through a perforation in the outer wall of the clamp plate 33, which may be depressed to release the ball from locking engagement with the post.

A post 50, similar to the posts 37 and likewise built up of sections so that the length thereof may be varied, is secured to 50 the clamp plate 33, in position to engage slots 35, of the leaves intermediate of the posts 37, and there is a socket block 43, in the opposite clamp plate 32, which is adapted to receive the end of the post 50, when the covers of the binder are clamped together. The socket 42 is preferably not provided with a locking device to grip the post as the locking devices for the posts 37 are sufficient to hold the binder together, 55 and additional locking devices would serve no useful purpose and would make it less convenient to disassemble the binder. These posts 37 and 50 are adapted to be engaged only by the notches 35, to hold the leaves 34 in the desired alignment and inasmuch as the notches 35 are entirely open at the outer

ends, the leaves may be readily inserted on the posts 37 and 50 and removed therefrom without any interference whatsoever.

For locking the leaves in the binder I have provided a locking post 51, consisting 70 of a sleeve 52, which telescopes the tube 53, and has the spring 54 interposed therein to normally hold the sleeve and stem extended, the entire separation of the sleeve and stem being prevented by the interengaged loops 55 and 56 of the sleeves 52 and 53 respectively. This stem or post 51, similarly to the other posts of the binder, is provided with sections as at 57 and a terminal plug 58, all threaded together so that the stem may be lengthened or shortened in accordance with the number of leaves to be contained in the binder, and there is a socket 42, in the clamp 32, and a corresponding socket 44, in the clamp plate 33 within which said sockets the ends of the post 51 are adapted to seat to hold and compress same intermediate thereof to lock the leaves in the binder. The sockets 42 and 44 are closed at the outer side of the clamp plate preferably by the wall of the clamp plate so that access may not be had to the ends of the resilient stem or post to release same without separating the clamp plates of the binder. The locking post 51 is arranged centrally of the posts 37 so as to be inserted normally through the central perforations 36 to lock the leaves in place, but as there is a perforation intermediate of each adjoining pair of notches and as they are all equally spaced, certain leaves may be arranged in offset relation with the other leaves and will still have aligning notches and perforations to facilitate proper placing of the said certain leaves and lock same in the offset position by means of the locking post 51. 100

The operation is as follows:

In using the binder and support, the detachable plate 8 is placed in the notches 7 so that the space between the plate 8 and the upper edge of the plate 5 will accommodate the number of leaves in the binder, and the brace 11 is engaged with the upper lugs 19, as shown by full lines in Figure 3, so that the binder may be placed flat thereon without cramping the parts and interfering with the convenient and easy disassembling of the binder. The binder is then laid upon the plate 8, with the back cover 9 thereagainst, and the front cover 26 is then detached by pressing the buttons 49, to release engagement of the locking mechanism with the posts 37, and the cover 26 is then removed and laid upon the plate 25, which is supported in the position shown in full lines in Figure 3 by engagement of the bracket 29 with the lower lugs 28. The posts 37 remain in engagement with the leaves on the plate 5, and thereby maintain the leaves in proper alignment, and the post 50, which is connected with the cover 26, rests on the plate 115 120 125 130

6, and serves as a guide to effect the proper alignment of the sheets transferred from the plate 5 to the plate 6. The locking pin 51, which normally remains in connection 5 with the leaves 34, when the cover 26 is removed, is then withdrawn from the perforations in the leaves and the leaves may then be removed without any interference whatsoever.

10 The plate 8 is then lifted upwardly and the brace 11 placed under the lugs 20, which thereby throws the upper edges of the leaves 34 forwardly in a different angular relation to the plate 5, and results in the upsetting 15 of the leaves somewhat in the manner shown in dotted lines in Figure 3, whereby the upper edges of the leaves are at successively higher elevations and are therefore easily fingered for selection and removal. Adjustment 20 of the plate 8 for upsetting the leaves may be further effected by means of the thumb screw adjustment of the brace 11 with the tubes 12. This adjustment however is intended primarily to compensate 25 for the different placing of the plate 8, in the notches 7, it being intended as a rule that the usual use of the binder in the support will necessitate only the adjustment 30 of the brace 11 against the lugs 19 and 20, which are suitably spaced to provide the proper adjustment to work with the binder and enable such adjustment to be made very quickly.

The leaves 34, resting against the cover 9, 35 in the tray are then selected and removed and entries made on all or part of them, and as the work thereon is completed they are transferred to a position against the cover 26, the alignment thereof in this position being readily effected by the engagement 40 of a slot 35, with the post 50, and in view of the equal spacing of the slots 35 and perforations 36, certain sheets may be offset with reference to the other sheets and will 45 still have slots and perforations thereof in alignment with slots and perforations of the other leaves on the cover 26. After the leaves 34 have been entirely transferred from the position against the cover 9 to 50 the position on the cover 26, the locking pin 51, is then inserted through the series of perforations 36 in the leaves so that the end thereof engages the socket 44 in the clamp plate 33, and the bracket 29, which 55 supports the plate 25, may then be released from engagement with the lugs 28 and placed in engagement with the lugs 27, as shown by dotted lines in Figure 3, so as to permit the cover 26 of the binder to lay down 60 somewhat flatter and enable the cover 9 to be more readily connected therewith. The cover 9 is then placed in position on the leaves 34, which are now supported on the cover 26, and the posts 37 are laid in their 65 respective slots and inserted in the openings

in the locking blocks 41, and at the same time the post 50 is inserted in the socket 43 in the clamp plate 32, and the end of the extensible locking pin 51 is directed into the socket 44, in the clamp plate 33, and the clamp plates are pressed together until they fit tight against the leaves therebetween. The extensible pin 51, which may be made in any length because of the sectional construction, is compressed by the approximation of the clamp plates 32 and 33, and engages in the sockets 42 and 44, and inasmuch as the outer ends of these sockets are closed the locking pin automatically holds its position and it is impossible to release the 70 same without disengaging and separating the clamp plates 32 and 33.

In order to insure locating the cover 9 and clamp plate 32 in proper position on the tray or rack, I have provided the pins 60, on the inner face of the plate 8, adjacent the lower edge thereof, which pins engage the perforations 61 in the outer wall of the clamp plate 32, when the clamp plate is placed in the proper position, and hold the 80 cover and posts of the binder in the proper position on the support.

For holding the other cover 26 of the binder in proper position on the support I make use of the buttons 49, which operate 95 the locking mechanism, and which project from the outer face of the clamp plate 33, and provide slotted perforations 62, in the lower edge of the plate 25, which receive 100 these pins and facilitate the placing of the cover 26 in position and also permit the clamp plate 33 to lie against the plate 25 without retracting the buttons 49. The plate 25 is also provided with slots 63, in alignment with the openings for the posts 105 in the locking blocks 41 so that the stems 37 may be inserted therethrough when the binder is clamped together. The lower end of the plate 6 is preferably recessed as at 64 to admit the clamp plate 33 therein so 110 that the edges of the leaves 34 will butt against the plate 6 and be held thereon in perfect alignment.

The lugs 24, whereby the plate 25 is pivotally connected to the plate 6, are bent so 115 that the plate 25 has the required pivotal movement and may also be laid down flat against the strips 1, by disengaging the bracket 29 from the strap 65 with which the plate 25 is provided and which is similar to the strap 21 of the plate 8, and the flange 4, at that side of the division plate 3, is provided with slots 66, to accommodate the buttons 49 and the projecting ends of the stems 37 at such time.

While I have shown and described my invention in a certain form, I am aware that various changes and modifications may be made without departing from the principles of my invention, and I therefore do not pur- 130

pose limiting the patent granted hereon otherwise than necessitated by the prior art.

I claim as my invention:

- 5 1. In a loose leaf binder support, oppositely inclined end members each having a plurality of vertically spaced slots, side members having projecting spurs adapted for detachable pivotal engagement with said slots, and adjustable braces for supporting said side members.
- 10 2. In a loose leaf binder support, oppo-

sitely inclined end members, and side members pivotally supported intermediate their ends and detachably connectible at their 15 lower margins with said inclined end members at different vertical heights.

In testimony whereof I have hereunto subscribed my name in the presence of two subscribing witnesses.

CHARLES R. FARGO.
